RAYMOND J. WEAN, OF WARREN, OHIO, ASSIGNOR TO THE WEAN ENGINEERING COMPANY, INC., OF WARREN, OHIO, A CORPORATION OF OHIO

METHOD AND APPARATUS FOR MAKING SHEETS

Application filed November 14, 1931. Serial No. 575,011.

My invention relates to a method and apparatus for making sheets and, in particular, to the manufacture of so-called black or steel sheets.

5 In the manufacture of sheets as now generally carried on, the apparatus employed comprises an "in and out" furnace, a stand of rolls and a doubler between the furnace and rolls. The usual method is to place 10 sheet bars of a length substantially equal to the width of the finished sheet in the furnace where they are heated to rolling temperature. The bars are removed from the furnace in pairs and are successively passed 15 through the rolls repeatedly to reduce their thickness. When the temperature of the material has fallen below the rolling value, the partially elongated sheets or breakdowns are matched or doubled and returned to the furnace for reheating. It is customary, however, to give each piece of material several 20 passes through the rolls before reheating. The material is handled manually at all times. When reheated, the material is again 25 rolled by giving it several passes through the mill. If heavy material is being made, it is generally possible to finish the rolling operation on the second heating. Thinner material may require a second doubling or 30 matching and third heating and rolling.

While the present system, as described above, is characterized by many objectionable features which contribute to a high cost of production, it was thought satisfactory 35 until the development of methods and apparatus for rolling wide strip. The low cost at which such strip could be produced seriously threatened the investment represented 40 by seven hundred sheet mills, amounting to nearly \$200,000,000.00, because the selling prices of wide strip soon fell below the cost of production of sheets made under the old practice. It is the object of this invention to 45 enable the old sheet mills to compete with wide strip, and installations which have been made already in accordance with the invention have proved that this object has been accomplished. The invention has been hailed 50 as a life saver to the sheet mills since it ena-

bles them to continue operation in spite of the competition of wide strip.

Another object of the invention is to make it possible for wide sheet bars to be handled in existing sheet mills.

In accordance with my invention, I employ a continuous furnace for heating the sheet bars or pairs prior to the initial rolling. A furnace of this type is charged at one end with cold bars which are carried through the 55 furnace on a conveyor and discharged at the other end in condition for rolling. A conveyor extends from the discharge end of the furnace to a stand of roughing rolls. My invention contemplates that the initial reduction in the material be effected by roughing rolls. A doubler is located on the exit 60 sides of the rolls which are in alinement with the furnace, and offset relative thereto. A conveyor extends from the discharge end of the furnace to a stand of roughing rolls. My invention contemplates that the initial reduction in the material be effected by roughing rolls. A doubler is located on the exit 65 sides of the rolls which are in alinement with the furnace, and offset relative thereto. A separate continuous furnace is provided for 70 heating packs of doubled breakdowns from the roughing rolls. The pack heating furnace is similar to the bar heating furnace, except that its conveyor is designed to handle packs instead of pairs. A stand of finishing rolls is in alinement with the pack furnace and is provided with mechanical handling equipment, such as a feeder and catcher, for advancing material to the rolls and supporting it as it emerges therefrom for 75 return over the top of the upper roll to the entrance side of the stand. A conveyor extends from the discharge end of the furnace to the feeding table. A doubler is located beyond the catching table and offset laterally from the line of the furnace and rolls. A return conveyor extends from the doubler to the entrance end of the pack furnace for 80 facilitating the handling of packs which require a third heating and rolling operation.

The method which I contemplate practicing with the apparatus above-mentioned will be described in greater detail after the apparatus has been more fully disclosed.

For a complete understanding of the invention, reference is made to the accompanying drawings, in which

Figure 1 is a diagrammatic side elevation of a portion of the apparatus constituting the invention;

Figure 2 is a sectional view substantially along the plane of line II—II of Figure 1;

Figure 3 is a view similar to Figure 1, showing the remainder of the apparatus; and

5 Figure 4 is a sectional view, taken substantially along the line IV—IV of Figure 3.

Referring in detail to the drawings, the apparatus constituting an embodiment of the invention includes a continuous pair heating 10 furnace 10, a stand of roughing rolls 11, a conveyor 12 connecting the discharge end of the furnace 10 with the roughing rolls, and a roughing doubler 13. The furnace 10 is of the continuous type and is provided with a 15 burner 14, a baffle wall 15 and a continuous traveling conveyor indicated diagrammatically at 16. This conveyor is preferably constituted by a plurality of chains traversing sprockets 17 driven by a motor 18. Other 20 details of the furnace are similar to those of that disclosed in the Drefein Patent No. 1,779,964.

The conveyor 12 preferably consists of a 25 plurality of gravity rolls. The roughing roll stand 11 and the doubler 13 are of known construction and do not require detailed description. It is to be noted, however, that the doubler 13 is located on the exit side of the rolls 11 and laterally offset from the common center line of the rolls 11 and furnace 10. This makes it possible to match or double 30 break-downs on the exit side of the rolls without interfering with the flow of material through the rolls.

35 A second furnace 19 serves to heat the packs formed in the doubler 13. The furnace 19 is similar to the furnace 10, being of the continuous type, but its conveyor, constituted by the chains 20, is specially adapted to carry 40 packs by means already well known. At the discharge end of the furnace 19, a gravity roll conveyor 21 serves to transfer packs to a mechanical roller's table or feeder 22. This device serves to advance packs through a 45 stand of rolls 23, constituting a finishing mill, and a catcher table 24, on receiving material from the rolls may be made to return it over the upper roll to the table 22 for repeated rolling. The construction of the roller's 50 table and the catcher table are well known, one example of this construction being shown in the McArthur Patent No. 1,750,534.

A doubler 25 is located on the exit side of the rolls 23 for doubling the packs a second 55 time in case thin material is to be rolled. From the doubler 25, a return conveyor 26 leads to the entrance end of the furnace 19, so that the redoubled packs may easily be passed through the furnace for reheating 60 prior to their second rolling operation in the finishing mill.

The method which I prefer to carry out by the apparatus set forth above may be described as follows:

65 Sheet bars of any width, either standard

narrow bars, wide thin bars, or breakdown bars, or plate strip for breakdown purposes, are fed into the entrance end of the pair heating furnace 10. The furnace burners and the conveyor speed are adjusted so that the time the material is discharged it has been heated to the proper rolling temperature. When discharged from the furnace 10, the material rolls down the conveyor 12 and is manually guided between the rolls of the 70 stand 11.

The roughing rolls 11 are adjusted to effect only a preliminary reduction in the thickness of the material. While this reduction requires several passes, by confining the total reduction effected in the roughing rolls to relatively narrow limits, the necessity for a wide variation in the roll set is avoided.

After the material has been reduced to the desired extent in the roughing rolls, it is transferred to the doubler. Instead of being doubled at this stage, however, the material may be matched, but, in either case, the doubling or matching takes place on the exit side of the rolls, or elsewhere apart from the 80 mill, so that there is no interference with the continued operation of the rolls in working the next pair. The production of initially reduced material is thereby expedited. I prefer to handle the material through the 85 rolls and return it back over the upper roll manually and to complete the reduction in a separate stand of rolls where mechanical handling equipment is available. Such equipment cannot successfully handle 90 sheet bars but, in order to take advantage of the high efficiency thereof, I effect the final reduction in a different stand of rolls provided with this equipment. I thus gain the 95 advantage of the mechanical handling equipment in the final rolling operation without causing any interference with the manual handling of the material during the initial reduction.

When the initially reduced material has 100 been matched or doubled, it is transferred to the entrance end of the pack heating furnace, either in single packs by means of a conveyor or in a pile comprising a number of packs, by 105 crane.

The heating of the packs is effected in a manner similar to that of the pairs or bars. By heating the pairs and packs in separate furnaces, the conveyors in each furnace may be designed specifically for a single purpose, 110 so that the operation of each is much more satisfactory than if a single furnace having a compromise design of conveyor were employed. The pair conveyor has heavy, substantial supports spaced closely adjacent each other. The pack conveyor has lighter supports spaced wider apart.

The packs discharged from the pack heating furnace 19 roll down to the conveyor 21 onto the feeder or roller table 22. This table, 115

under the control of an operator or roller, feeds the material between the rolls of the finishing stand 23. On the exit side of the rolls, the catcher table 24 receives the material, returns it over the top of the upper roll, and it is then again passed between the rolls. This operation is repeated until the sheets comprising the pack have been reduced to the desired extent or until the pack has become too cool for further rolling. The pack is then transferred to the doubler 25 where it is redoubled, or similar packs may be re-matched, when a further reduction in the thickness of the sheets is to be made. In this case, the redoubled, re-matched pack is conveyed on the conveyor 26 to the entrance of the pack heating furnace 19 for reheating. The final steps of the method are determined solely by the desired characteristics of the finished product. If comparatively heavy sheets are to be produced, the final reduction can be completed on the first heating of the packs. If thinner sheets are being rolled, the second matching or doubling and third heating and rolling will be resorted to. By limiting the finishing mill to the final reductions in thickness, a wide range of adjustment of the rolls is again avoided and at the same time the quality of the product is improved, because the finishing rolls are not subject to the rapid deterioration characterizing the operation of the roughing rolls as a result of the heavy reductions which they are called upon to make. After the final rolling, the packs are piled for shearing into individual sheets. The redoubling or re-matching operation takes place on the opposite side of the finishing mill and again prevents the interruption of the rolling of subsequent packs in the mill. I also contemplate the use of a continuous automatic polisher for the rolls of both the roughing mill 11 and the finishing mill 23. This device, which is well known, eliminates the necessity for shutting down the mill for refinishing the rolls and increases the efficiency of the plant.

It will be apparent that the method and apparatus disclosed herein make possible the manufacture of sheets by existing plants with an extremely high degree of efficiency and at a comparatively low cost. The invention transfers the heavy laborious work which has been performed manually heretofore, to machines, but relies on supervision of operators at all stages. The necessary manual labor is thus used much more efficiently than has been the case in the old methods. The economies and uniformity of product which result from the use of the continuous heating furnace can now be obtained, by the use of the invention, in all stages of the manufacture. The continuous furnaces, furthermore, make it possible for the manufacturer to choose from several varieties of raw material,

namely, wide sheet bar, conventional bar, or plate strip.

The advantages flowing from the use of separate roughing and finishing rolls have already been mentioned, as well as those resulting from the location of the doubler on the exit side of the rolls in both cases. These advantages include the fact that mechanical handling equipment for cooperation with the rolls is used where it can be employed with satisfactory results without interfering with manual handling during the roughing reduction where mechanical equipment is not practical.

As previously stated, the invention, in numerous installations already in operation, has proved that it enables old style sheet mills to compete with wide strip mills after the improvements herein described have been incorporated in the present sheet mills. The invention thus protects the investment which has been made in the large number of sheet mills now in existence in the amount of nearly \$200,000,000.00, which would otherwise have to be written off because of the scrapping of the old type of sheet mills which would necessarily follow from the competition of the wide strip mills. In one instance, a manufacturer, after installing a wide strip mill at an expense of \$15,000,-000.00 put in the applicant's system to rehabilitate his old sheet mills. The invention permits the old sheet mills to compete with wide strip mills, because it increases the production and lowers the manufacturing cost. While lowered labor cost is a part of this reduction in total cost, the greater portion of it is due to the greater efficiency with which the new system operates. All the equipment is used to much better advantage with a resultant increase in output. The rolls are effective a greater portion of the time and the mechanical equipment with supervising operators speeds up the flow of production. Another advantage of the invention is that the old mills were not adapted to the handling of wide sheet bar which can readily be manipulated in the system of my invention.

Although I have illustrated and described herein a specific embodiment of the apparatus and a specific example of the method constituting my invention, together with possible alterations in the method, it will be understood, of course, that the invention is not limited by the disclosure since it may be embodied and practiced otherwise than herein described and illustrated. Numerous changes in both method and apparatus may be made without departing from the scope of the appended claims.

I claim:

1. In a sheet mill, the combination with a continuous bar heating furnace, a stand of roughing rolls in alinement therewith for ef-

fecting a preliminary reduction only in the material, a conveyor between the furnace and rolls, and a doubler on the exit side of the rolls, offset relative thereto, of a continuous pack heating furnace, a stand of finishing rolls in alinement therewith for effecting final reduction of the material into sheet form, mechanical handling equipment for feeding and catching material at the finishing rolls, and a return conveyor from the rolls to the entrance of the pack heating furnace.

2. A method of making sheets including the steps of feeding sheet bars through a heating furnace, rolling the heated bars through roughing rolls to effect only an initial reduction of the material and manually returning the rolled material over the rolls for repeated passes therethrough, matching the material after the final rolling in the roughing rolls, passing the matched material through a continuous pack-heating furnace and finishing rolls, doubling the matched material on the exit side of the finishing rolls, repassing the material through the pack-heating furnace, and effecting a final reduction thereof in said finishing rolls.

3. A method of making sheets including the steps of feeding sheet bars through a heating furnace, rolling the heated bars through roughing rolls to effect only an initial reduction of the material and manually returning the rolled material over the rolls for repeated passes therethrough, matching or doubling the rolled material into packs, passing the matched or doubled packs through a heating furnace, mechanically handling the heated packs to pass them repeatedly through and over rolls for effecting further reduction, re-matching or re-doubling the packs, and repassing them through the pack heating furnace and said last-mentioned rolls for final reduction.

4. In a sheet mill, the combination with a continuous furnace having a conveyor adapted to carry bars or pairs, a stand of roughing rolls in alinement therewith, a doubler on the exit side of the rolls and offset relative thereto, a continuous furnace for heating packs from said roughing rolls and doubler having a conveyor adapted to carry packs only, a stand of finishing rolls in alinement with the pack-heating furnace, and a doubler on the exit side of the finishing rolls.

5. In a sheet mill, the combination with a continuous bar heating furnace, a stand of roughing rolls in alinement therewith for effecting a preliminary reduction only in the material, and a conveyor between the furnace and rolls, of a continuous pack heating furnace, a stand of finishing rolls in alinement therewith for effecting final reduction of the material into sheet form, mechanical handling equipment for feeding and catching material at the finishing rolls, a doubler on

the exit side of the rolls and offset laterally thereof, and a return conveyor from the rolls to the entrance of the pack heating furnace.

6. In a sheet mill, the combination with a continuous bar heating furnace, of roughing rolls for receiving bars from said furnace and effecting a preliminary reduction thereof, means for conveying the bars from the furnace to the rolls, a doubler for rough rolled material, a continuous pack heating furnace, finishing rolls for receiving material from said pack heating furnace and effecting final reduction thereof into sheet form, mechanical handling equipment for feeding and catching material at the finishing rolls, and means for conveying material from the finishing rolls to the entrance of the pack heating furnace.

7. In a sheet mill, the combination with a continuous bar heating furnace, of roughing rolls for receiving bars from said furnace and effecting a preliminary reduction thereof, means for conveying the bars from the furnace to the rolls, a continuous pack heating furnace, finishing rolls for receiving material from said pack heating furnace and effecting final reduction thereof into sheet form, mechanical handling equipment for feeding and catching material at the finishing rolls, and means for conveying material from the finishing rolls to the entrance of the pack heating furnace.

8. In a sheet mill, the combination with a continuous bar heating furnace, of roughing rolls for receiving bars from the furnace and effecting a preliminary reduction thereof, means for conveying the bars from the furnace to the rolls, a continuous pack heating furnace, finishing rolls for receiving material from said pack heating furnace and effecting final reduction of the same into sheet form, and mechanical handling equipment for feeding and catching material at the finishing rolls.

9. In the method of producing sheets by rolling, the steps comprising passing the material to be rolled into and through a furnace in one direction only, discharging the material from said furnace in said one direction only, and subjecting the material to rough rolling repeatedly in a given stand of rolls, passing the rough rolled material into and through a second furnace in one direction only, discharging material from said second furnace in said one direction only, subjecting the material repeatedly in a given stand of rolls to a finish rolling operation, and mechanically handling the material during said last mentioned rolling operation.

In testimony whereof I have hereunto set my hand.

RAYMOND J. WEAN.
